UNITED STATES PATENT OFFICE

152,157

DESIGN FOR A HAND PROTECTING GRIP

Llewellyn T. Jones, Akron, Ohio

Application November 6, 1946, Serial No. 134,547

Term of patent 3½ years

(Cl. D17—5)

To all whom it may concern:

Be it known, that I, Llewellyn T. Jones, a citizen of the United States, residing at Akron, in the county of Summit and State of Ohio, have invented a new, original, and ornamental Design for a Hand Protecting Grip, of which the following is a specification, reference being had to the accompanying drawing, forming part thereof.

In the drawing:

Figure 1 is a side elevational view of a hand protecting grip, showing my new design;

Figure 2 is a top plan view;

Figure 3 is a bottom plan view;

Figure 4 is an end elevational view, and

Figure 5 is a section on line 5—5 of Figure 1.

I claim:

The ornamental design for a hand protecting grip, as shown.

LLEWELLYN T. JONES.
